BROOCH OR SIMILAR ARTICLE

Frona N. Jost, Honolulu, Territory of Hawaii

Application April 17, 1950, Serial No. 9,270

Term of patent 3½ years

(Cl. D45—19)

To all whom it may concern:

Be it known that I, Frona N. Jost, a citizen of the United States, residing at Honolulu, in the county of Honolulu and Territory of Hawaii, have invented a new, original, and ornamental Design for a Brooch or Similar Article, of which the following is a specification, reference being had to the accompanying drawing, forming part thereof.

Fig. 1 is a front elevational view of a brooch or similar article showing my new design.

Fig. 2 is a side elevational view thereof.

The dominant features of the design are shown in full lines in the drawing.

I claim:

The ornamental design for a brooch or similar article, substantially as shown and described.

FRONA N. JOST.
